UNITED STATES PATENT OFFICE.

HUGO E. BOHL, OF BAYONNE, NEW JERSEY, ASSIGNOR TO RADIANT LIGHTING FIXTURE CO., INC., A CORPORATION OF NEW YORK.

DESIGN FOR A RING FOR LIGHTING FIXTURES.

Application filed May 7, 1924. Serial No. 9,510. Term of patent 3½ years.

To all whom it may concern:

Be it known that I, HUGO E. BOHL, a citizen of the United States, and a resident of the city of Bayonne, county of Hudson, and State of New Jersey, have invented a new, original, and ornamental Design for a Ring for Lighting Fixtures, of which the following is a specification, reference being had to the accompanying drawing, forming a part hereof.

The figure in the drawing is an inverted plan view of the plate. The portion indicated in full line outline in the drawing is ornamented in the same manner as the portion more fully illustrated.

I claim:

The ornamental design for a ring for lighting fixtures substantially as shown and described.

HUGO E. BOHL.
